UNITED STATES PATENT OFFICE.

CHARLES WADE TUDOR DAVIES, OF NEW YORK, N. Y., ASSIGNOR TO THE GOOD FORM MANUFACTURING COMPANY, OF NEW YORK, N. Y., A CORPORATION OF NEW YORK.

NECKTIE.

No. 817,864.

Specification of Letters Patent.

Patented April 10, 1906.

Application filed March 5, 1904. Renewed March 9, 1906. Serial No. 305,132.

To all whom it may concern:

Be it known that I, CHARLES WADE TUDOR DAVIES, a subject of the King of Great Britain, residing at New York city, county of New York, and State of New York, have invented certain new and useful Improvements in Neckties, of which the following is a specification.

This invention relates to neckties, and is an improvement on the neckties disclosed in my Patents No. 605,947, dated June 21, 1898, and No. 615,435, dated December 6, 1898, being more particularly designed to improve the type of reversible necktie disclosed in my Patent No. 615,435.

The present invention has reference more particularly to reversible neckties—such, for instance, as those known as "string" ties and "ascots"—although its application is not necessarily thus restricted.

In my Patent No. 605,947 I have disclosed the broad idea of providing tabs on a necktie substantially at the juncture of the neckband and the tying ends thereof for engagement with the front fastening of the collar to hold the neckband on the collar and relieve the strain from the bow or knot when the necktie is tied, and in my Patent No. 615,435, in adapting this principle to neckties, I have employed a member having loops or parts for engaging the front fastening of the collar and arranged relatively to the necktie in such manner that the necktie can be slipped or adjusted on or relatively to said member to bring the bow or knot in proper position at the front of the collar. In that patent I have shown how stitches can be used as guides for the attaching member, permitting said member to slip therethrough and to prevent the loops from snapping in between the folds or plies of the necktie where the user cannot conveniently reach them.

The present invention has for its object the provision of attaching devices, such as tabs, loops, or equivalent means, in connection with a reversible necktie for engaging the front collar-fastening and arranged to be used on either side of the necktie, according to which side of the necktie is used as the outer side, and the invention also aims to make provision for a necktie, of an attaching-tab, and an eyelet through which the tab can be drawn to cause it to project from either side of the necktie, according to which side is used as

the outer side, and in the accomplishment of these objects a tab or fastening is provided which may be elastic or inelastic and which is fixedly anchored or connected to the necktie, and thus distinguished in its construction from the necktie shown in my Patent No. 615,435; but in another aspect the invention has for its object the provision, in connection with a necktie, of a tab or attaching device for connection to the front fastening of the collar, which is fixedly connected or anchored to the necktie, and an eyelet through which said tab can be folded, thereby making provision for positioning the tab or fastening, so that it may be engaged with the fastening of the collar, or leaving it optional with the user to omit the use of said tab as a fastening and arrange and tie the necktie as with ordinary neckties. In any instance the invention contemplates the use of an elastic or inelastic tab or fastener.

Certain forms which the invention may assume are shown in the accompanying drawings and set forth hereinafter; but I am well aware that such are not the only forms involved in the invention, and I therefore do not limit myself to the forms which are shown and described.

In the accompanying drawings, Figure 1 is a view of one form of the invention applied to an ordinary collar, showing the tabs or fastening devices connected to the front collar-fastening and the tying ends hanging free, the tabs in this form being inelastic and the invention being shown in connection with a string tie which is intended to be formed into a bow; Fig. 2, an enlarged perspective detail view showing more clearly the manner in which the tab projects from between the two plies of the necktie and also showing the eyelet; Fig. 3, an edge view, dotted lines representing how the tab can be pushed through the eyelet so as to project from the opposite side of the necktie; Fig. 4, a perspective detail showing the seam of the folds or plies of the necktie ripped open and the folds spread apart to illustrate how an opening is formed in each ply and how the tab is secured between the plies of the necktie; Fig. 5, a view showing how the tabs or fastening devices may be formed of elastic material; Fig. 6, a section on line 6-6 of Fig. 5, illustrating how the elastic tabs are connected to the necktie farther back than when inelastic tabs are

- used in order to permit the elastic to stretch; Figs. 7 and 8, details illustrating the adaptation of the invention to that form of necktie comprising two double plies or folds which are 5 not connected along one edge, showing an inelastic tab; Fig. 9, a view showing how an elastic tab is used on the necktie shown in Figs. 7 and 8, and Fig. 10 details showing how a loop or round elastic can be used.
- 10 In the drawings the invention is shown in connection with string or bow neckties in each instance; but it is not restricted to this particular type of necktie nor to the forms illustrated.
- 15 Referring first to Figs. 1, 2, 3, and 4, the string necktie consists of a neckband 1 and tying ends 2 and 3. The attaching or fastening tabs or devices 4 and 5 are connected to the necktie at the junction of the neckband 20 and the tying ends 2 and 3 thereof, as shown more clearly in Fig. 1. In the present instance I have shown tabs; but I do not thereby limit myself to the use of tabs only, as other fastenings can be used. The tabs 4 and 5 have a buttonhole 6 therein, and they 25 button over the front collar-button 7, one on top of the other. This holds the neckband 1 on the collar 8 and relieves the tying ends 2 and 3 from all strains, so that they can be 30 manipulated as desired to form the knot or bow, and it will be understood that in this form of the invention where the tabs are made of some inelastic material they are connected to the necktie at the proper points to 35 engage the collar-button 7, and a buyer in purchasing a necktie equipped with my improvements designates the number of the collar with which the necktie is to be worn and purchases a necktie having its tabs arranged 40 for that size collar.
- 45 The invention as described embraces the broad conception of my Patent No. 605,947. The present improvements relate to the manner of attaching the tabs or fastenings to the necktie and the use of an opening for the tabs to pass through, as set forth heretofore.
- 50 In Figs. 1, 2, 3, and 4 the necktie is of the reversible kind, so that either side can be used as the outer face of the necktie, and consists of the plies 9 and 10, connected by the seam 11 and preferably provided with a filling-strip 12. The tabs 4 and 5 are of similar construction and similarly connected to the necktie, and hence a description of one will suffice. The tab has its end 13 lying between the plies 9 and 10 and is stitched or otherwise fastened at 14 to the fabric of the necktie on either side or to the filling 12 within the necktie on either side without any stitching in the 55 fabric of the tie, leaving the balance of the tab free. In plies 9 and 10 are formed eyelets 15 and 16, which coincide, and these can be stitched together along their margins to form, in effect, a single eyelet, which is in reality formed of the two separate incisions or 60 eyelets 15 and 16. The tab projects through these eyelets 15 and 16 out on one or the other side of the necktie, according to which side of the necktie is to be used as the inner side, it being understood that the user simply 65 pushes the tab through the eyelets 15 and 16 from one side to the other of the necktie to bring the tab to that side of the necktie which will be the side lying adjacent the collar, for it will be understood that the tabs 70 project from the inner side of the necktie when the latter is on the collar, as shown in Fig. 1. Provision is thus made for the use of my improvements on reversible neckties, and when the tying ends 2 and 3 are made into 75 the knot or bow they cover up the openings on the outside of the necktie. In this form of the invention it is not to be understood from Fig. 4 that the free end of the tab lies between the plies of the necktie, because Fig. 80 4 is simply illustrative and the tabs project from one side or the other of the necktie, as shown in Figs. 2 and 3, according to which position is necessary.
- 85 Referring to Figs. 5 and 6, I have here shown the manner in which a tab 17, of elastic material, may be employed. Where an elastic tab is employed, the tab is intended to be manipulated the same as the inelastic tab of Figs. 1, 2, 3, and 4; but instead of stitching 90 the elastic tab of Figs. 5 and 6 to the necktie immediately adjacent the eyelets such elastic tab has a portion 18 thereof lying loosely between the plies and stitched at the point 19 to the necktie, which permits the part 18 to 95 freely stretch as the tab 17 is manipulated or attached to the collar-button, thus affording a connection between the neckband and the collar-button, which will adapt the neckband to the collar even if the tabs are not positioned on the necktie as for a size exactly the same as the collar, and in this form also, even though the tabs are positioned correctly for the given size of collar, the elasticity of the tabs firmly holds the neckband on the collar 100 at all times. It will be understood that at the point 20 the ply 10 is loose.
- 105 In Figs. 7, 8, and 9 I show how the invention is adaptable to that form of necktie at present known to the trade which embraces 110 two plies 21 and 22, which simply are folded upon each other along the crease 23 and have their edges 24 and 25 entirely disconnected, and thus differs from the form of necktie shown in the preceding figures, where the 115 seam or connection 11 is provided. The tab of Fig. 7 is in all respects the same as the tab of Figs. 1, 2, 3, and 4, being connected in the same manner; but it will be understood that when the invention is adapted to this form of necktie the tab can be drawn in and positioned entirely between the plies 21 and 22, so that the necktie can be used as it ordinarily 120 would be used if no tabs were provided. In this form of the invention, as in other forms, 125 130

it will be understood that one of the coincident eyelets can be dispensed with, if desired, two eyelets being provided in order that the invention may be adapted to reversible ties; 5 but with such ties as are not reversible only one eyelet for each tab is necessary. With the form of necktie shown in Fig. 7 a piece of elastic 26 can be used, as shown in Fig. 9, in order to permit the tab to stretch, this piece 10 of elastic 26 being connected at one end to the necktie and at the other end to the tab, which latter is of non-elastic material.

Fig. 8 illustrates how the tabs of Figs. 7 and 9 can be drawn through either eyelet, according to which side of the necktie is to lie 15 next to the collar.

In the form assumed by the invention in Fig. 10 I substitute for the flat tabs shown in the other figures elastic or inelastic loops 27, 20 which are secured in between the plies of the necktie at 28 and can be pushed through an eyelet 29 to one or the other side of the necktie. In this form of the invention the eyelet 29 is preferably arranged lengthwise of 25 the necktie instead of transversely thereto, as in the other forms.

Having thus described my invention, what I claim as new, and desire to secure by Letters Patent, is—

30 1. The combination with a necktie having superposed plies and provided with an opening extending completely through both of said plies, of a fastening member having means for engaging the collar-button, said fastening member having a portion located 35 between the plies of the necktie and anchored or secured to the necktie and which is adapted to be brought through the opening in the necktie to project from either side of said necktie.

40 2. The combination with a necktie having superposed plies and an opening extending entirely through said plies from side to side of

the necktie, of a tab having an eyelet or opening for engagement with the collar-button, 45 said tab having a portion thereof secured or anchored between the plies of the necktie, and said tab being adapted to be brought through the opening in the necktie to either side of said necktie.

50 3. The combination with a necktie consisting of superposed plies, each having an opening therethrough, of a tab having an opening to engage the collar-button, said tab having a portion thereof located between the plies of 55 the necktie and anchored or fastened to the necktie and having a free portion adapted to be brought out through either of the openings aforesaid.

4. A necktie having openings or eyelets located substantially at the junction of the neckband and its respective tying ends, and fastening-tabs which are respectively secured or anchored to the necktie adjacent the eyelets or openings aforesaid and each having a 60 free portion, for engagement with the front collar-button, adapted to be passed through the openings or eyelets so as to lie on either side of the necktie.

5. A necktie having buttonhole-tabs at its 70 neckband portion and slits for the tabs to be passed to either side of the tie, said tabs being sewed within the plies of the tie to conceal their ends.

6. A necktie having buttonhole-tabs at its 75 neckband portion and slits for the tabs to be passed to either side of the tie, said tabs being sewed within the plies of the tie to conceal their ends, and being made elastic to secure a proper fit for the tie.

In testimony whereof I hereunto affix my signature in presence of two witnesses.

CHARLES WADE TUDOR DAVIES.
